DESCRIPTION

FIG. 1 is an end view of a ratchet wrench that incorporates my new design;
FIG. 2 is a left side view thereof;
FIG. 3 is a top view thereof;
FIG. 4 is a bottom view thereof;
FIG. 5 is an end view thereof, taken from the end opposite that of FIG. 1; and,
FIG. 6 is a cross-sectional view thereof taken along line 6—6 of FIG. 4.
The left side view (not shown) is identical to the right side view of FIG. 2.
